UNITED STATES PATENT OFFICE.

CHARLES J. ELLIS, OF CINCINNATI, OHIO, ASSIGNOR TO THE CINCINNATI CAR COMPANY, OF CINCINNATI, OHIO, A CORPORATION OF OHIO.

RAILWAY CAR.

Application filed December 14, 1923. Serial No. 630,603.

To all whom it may concern:

Be it known that I, CHARLES J. ELLIS, a citizen of the United States, residing at Cincinnati, in the county of Hamilton and State of Ohio, have invented certain new and useful Improvements in Railway Cars, of which the following is a specification, reference being had therein to the accompanying drawing.

10 This invention relates to improvements in railway cars, more particularly to means for preventing the side-sway of articulated cars, that is, cars whose adjacent ends are supported by one truck common to both 15 cars.

15 The first object of this invention is to obtain the same control as to limiting the rolling or side sway of articulated cars that is obtained in unarticulated cars by means 20 of the side bearings on the bolsters; and to do this notwithstanding that the bolster of the articulated cars at or near its ends is not beneath the car body.

25 This object is carried into effect through utilizing a vestibule mounted on adjacent car platforms at two opposite sides of its center, in connection with a bolster which is beneath two intermediate opposite sides of the vestibule center, combined with 30 spring side-bearings which exert their limitations to the side sway of the car bodies through the vestibule structure.

35 My organization consists, essentially, of resilient side-bearings mounted on the truck-bolster at points under the vestibule and adapted to hold the vestibule from swaying laterally, and thereby to cause the vestibule to check the lateral swaying of the car body. The vestibule overlaps the platforms 40 of the cars, so that the resistance the side-bearings offer against side swaying of the vestibule is thus transmitted to the car platforms through the vestibule.

45 In the accompanying drawings forming part of this specification, Fig. 1 is a transverse vertical view of the truck, the vestibule and the end of a car, partly in section and partly in elevation.

50 Fig. 2 is a partial plan view and horizontal section of the truck, the vestibule and the adjacent platforms of two cars.

55 Fig. 3 is a longitudinal section through the truck, the platforms of two adjacent cars and of the vestibule.

60 Fig. 4 is a sectional view on the line

4—4 of Fig. 1 showing the bolster, one of the resilient side-bearings, a portion of the car platforms and of the vestibule.

In the drawings the numeral 1 designates, generally, a railway car truck comprised of 60 wheels 2, and a bolster 3. The other details I do not show, because it is not essential to an understanding of this invention.

On this bolster is mounted a bearing plate 4 having two bearings sockets 5. In these 65 sockets are mounted, respectively, the pivot trunnion 6 of one car and the pivot trunnion 7 of the other car. These trunnions are formed with flanges or extensions 8, by which they are secured to the respective 70 platforms, thus constituting trunnion plates. There are other features of this double bearing which are unnecessary to describe because this bearing itself forms no part of my invention and is merely shown and thus 75 generally referred to because it is the preferred mode of articulating the cars with which my invention is designed to be used.

Referring now to the features which constitute this embodiment of my invention, 80 the numeral 9 designates yokes mounted on the truck bolster, each near the outer end thereof. As seen in Fig. 4, these yokes are secured by bolts 10 and are elevated somewhat above the bolster by blocks 11. With 85 each yoke is associated a pair of springs, one of which, 12, I denominate as a resistance spring and the other, 13, a pressure spring. Within these springs is a rod 14 fitted with nuts 15, with washer seats 16 90 interposed between the nuts and the springs to properly position the spring with reference to the rod. By preference I also use discs 17 against which the springs contact.

It will now be observed that the resistance 95 spring 12 acts to yieldingly anchor or maintain the rod 14 against the exertions of the pressure spring when the latter is compressed by the movements of the vestibule, to be presently described. It will further be 100 understood that this yoke, rod and these two springs constitute a resilient side-bearing carried by the bolster and located, as seen in Fig. 2, at points under the vestibule between and somewhat remote from the platforms of 105 the adjacent cars. Thus I have provided resilient side bearings which, as will presently appear, act on the vestibule, to cause it to react on the car platforms to resist side-swaying movements of the cars.

Referring now to the vestibule and its relations to the car platforms, the numeral 18 designates the vestibule generally which is composed of a central base 19 underlaid with 5 a reinforcing band 20, a top or roof 21 and curved side walls 22. The side walls terminate at convenient points such as shown at 23, to leave openings or doorways through which passengers may travel from one car 10 platform to the other. The vestibule rests upon these platforms which are designated 24 and are supported on the bolster 3 through the trunnions 6 and 7 as before pointed out.

Thus it will be understood that the vestibule 15 rests upon and rides on the platforms and overlaps them at diametrical points, while at intermediate points the vestibule is acted on by the pressure springs 13, which exert a downward pressure on the floor 19 20 and tend to hold the vestibule in firm contact with the platforms, yet without preventing the platforms from changing their relative position to the vestibule when going around curves.

25 The springs press upward on the rods 14 and the resistance springs resist that pressure by holding downward on the bolts. Thus any force which tends to compress the pressure spring is yieldingly resisted not 30 only by that spring but by the resistance spring, acting through the rod 14.

The forces which tend to create pressure against the pressure springs are those forces which arise from the tendency of the cars 35 to rock sidewise or undergo what is known as side-sway. When this takes place, the platform at the side which rises will tend to lift on the vestibule, but the pressure spring 13 on that side of the vestibule will 40 immediately resist this lifting tendency and hold down on the vestibule and in turn thereby hold down on the platform, with the result that the side-sway is checked or eliminated according to violence. And likewise 45 any swaying of the car body in the other direction, and tendency to lift the vestibule on the opposite side will be resisted by the action of the pressure spring on that side of the vestibule.

50 Thus it will be understood that the vestibule is resiliently but forcibly held down on the platforms as against any lifting movement of either side of either platform, due to side-sway. In the drawings, see Fig. 55 2, the places where the lifting tendency of the platforms on the vestibule are indicated by the space between the letters *a* and *b*, *c* and *d*, as to one platform, and *e* and *f* and *g* and *h* as to the other platform. In other 60 words, as the cars tend to rock laterally in side swaying, the platforms are resisted by the vestibule in the spaces from *a* to *b* and *c* to *f*, if the sway is from that side, and in the spaces from *c* to *d* and *g* to *h*, if the sway is 65 from that side. I wish it to be particularly

observed that although these resilient side bearings are at points somewhat remote from the car platforms and at places not under the platforms, but between them, still through the intermediary of the vestibule I utilize the 70 resistance forces of these bearings in doing the ultimate thing of checking or eliminating the side-sway of the cars.

It will further be observed from Fig. 2, 75 that there are four points of contact or connection between the truck bolster on the one part and the vestibule and two car platforms on the other part. Then that all of these contacts or connections are flexible. Therefore, there is freedom of movement of the 80 parts for the accommodation of the infinite number of relative positions they assume while travelling in use. Thus under all conditions the contingency of side-sway of the car body may be checked or prevented 85 through the vestibule, the resilient side bearings and the car platforms while on the other hand there is perfect freedom of movement of each car respectively to the bolster.

Having thus fully described my invention, 90 what I claim as new and desire to secure by Letters Patent is:—

1. In a railway car, the combination with a truck bolster and cars articulated thereon, 95 of a vestibule partly positioned over the platforms and partly over the bolster, and resilient side bearings acting between the bolster and the vestibule to cause the vestibule to resist swaying movements or tendencies of the platforms.

2. In a railway car, the combination with a truck bolster and the platforms of adjacent cars articulated on the bolster, of a vestibule forming a passageway from platform to platform, overlaying parts of each platform and at intermediate portions overlaying the bolster, and resilient side bearings including springs which act downward on the vestibule to cause it to resist side-sway movements of the platforms.

3. In a railway car, the combination with a truck bolster and the platforms of adjacent cars articulated on the bolster, of a vestibule forming a passageway from platform to platform, overlaying parts of each platform and at intermediate portions overlaying the bolster, and resilient side bearings mounted on the bolster and including pressure springs which act downward on the vestibule and resistance springs which co-operate with the pressure springs.

4. In a railway car, the combination with a truck bolster and resilient side bearings comprising yokes mounted on the bolster, rods carried by the yokes, resistance springs within the yokes acting downward on the rods and pressure springs on the rods, of a vestibule within which the pressure springs are located and adapted to be pressed downward by said springs, and car platforms 120

partly located under portions of the vestibule.

5. In a railway car, the combination with a truck bolster, of resilient side bearings each comprising a yoke, a rod mounted therein, a resistance spring adapted to act downward on the rod and a pressure spring adapted to react upward on the rod.

6. In a railway car, the combination with a truck bolster, of resilient side bearings located one near each end of the bolster and each comprising a yoke secured to the bolster, a rod mounted in the yoke, a resistance spring acting at one end on the yoke and at the other on the rod, and a pressure spring adapted to act at one end against a vestibule

structure and reacting at the other end on the rod.

7. In a railway car, the combination with a truck bolster, side bearings carried thereby, and two adjacent car platforms, a pivotal connection between each platform and the bolster and a vestibule positioned to overlap the adjacent portions of the platform and to extend over the side bearings on the bolster, whereby a four-point contact is provided, two points between the platforms and bolster and two other points between the vestibule and bolster. 20 25

In testimony whereof I affix my signature.

CHARLES J. ELLIS.
